UNITED STATES PATENT OFFICE.

SPENCER OTIS, OF BARRINGTON, ILLINOIS.

GRAVITY-FEED BOILER-WASHING SYSTEM.

Application filed October 12, 1922. Serial No. 593,944.

This invention relates to a system or apparatus through means of which the contents of a locomotive boiler can be blown off, and the heat units thereof salvaged in 5 water collected for return to the boiler; and the invention has for its primary object to utilize gravity for feeding water in order that the apparatus may be greatly simplified and the cost of the system proportionately reduced.

The invention proceeds upon the principle of storing, at an elevation well above the level of the locomotive stalls, the water that is to be delivered to the locomotives, 15 thereby making it possible to utilize gravity for feeding the water at the necessary head of pressure for washing out and refilling the boiler, and availing of the levity of the volatiles of the blown off products to raise 20 them to or above the storage level where they meet the condensing water which attains the same high level under service pressure. Preferably the separator, which permits escape of the volatiles from the blown 25 off products, is given a sub-surface location so that the locomotive can drain into it by gravity in case it should be desired to largely or wholly relieve the boiler of steam pressure by direct discharge into the 30 vapor pipe; and preferably also there is the usual circulating line for return flow from the hot water supply pipe in order to keep up the temperature in the latter. But flow of water in this circulating line 35 is limited to that necessary to keep up the temperature, and the pump required, therefore, is of proportionately small capacity, it being required merely for the load of getting the return water up to the level of 40 the storage tank. The returned water of circulation, as well as exhaust steam from the pump engine, will preferably be delivered to the condenser in accordance with known practice, and the usual method of 45 controlling the supply of fresh water to the condenser, through means of a thermostat, will preferably be employed.

In the accompanying drawing, which 50 illustrates the invention partly in elevation and partly in section, 1 represents a locomotive station of a terminal house, and 2 represents the blowoff line leading therefrom to a separator 3. A connection 4 rises from the floor of the terminal house 55 to receive blown off products instead of dropping from an overhead line as usual,

and the separator 3 is in the form of a sub-surface tank or sump which is sufficiently below the level of the station 1 to render gravity available in emptying the boiler 60 when there is insufficient steam pressure for this purpose, or in assisting the discharge by reducing the resistance to be overcome by the boiler pressure, and therefore hastening the time of boiler discharge. 65

Rising from the separator 3 is a vapor pipe 5 which delivers into a condenser 6 of known construction at such an elevation above the station to feed water to the station by gravity. Condenser 6 is supplied 70 by the usual cold water pipe 8 under control of valve 9 that is responsive to thermostat 10 in the condenser. Leading from the tank 7 is a hot water supply pipe 11 which extends past the station 1 and past as many other stations as may be desired, and this supply pipe 11 is provided with one or more drops 12 terminating in washout connection 13 and filling connection 14 within reach of a locomotive occupying the station 1. Gravity alone is relied upon to deliver 80 water through the connections 13 and 14 with a sufficient head of pressure to serve the purposes for which these connections are provided. Connected with a remote end of the hot water supply pipe 11 is a circulating line 15 of capacity sufficient to maintain circulation through the pipe 11 and keep up the temperature of water even in remote parts thereof, and this circulating 85 line 15 is made to discharge into condenser 6 in accordance with known practice, but in accordance with the present invention has a circulating pump 16 interposed in the pipe 15 of a capacity which is suitable 90 merely for the purpose of keeping up the circulation and overcoming the head of pressure necessary to get the return water up to condenser 6. In this way a very much smaller pump can be employed than is required in systems in which the entire flow 95 over the supply line 11 is developed by pumping.

17 represents a steam line which is tapped 100 into the pump at 18 and which also has a branch 19 controlled by valve 20 and leading to the condenser 6, so that in the event the water supply in the tank 7 is low, steam 105 may be delivered to the condenser through the pipe 19, and this, acting on thermostat 10 will open the cold water pipe 8 and develop a fresh supply of hot water. Pump 110

16 has its exhaust pipe 21 tapped into the vapor pipe 5, so that not only are the heat units from the exhaust conserved in the condenser 6, but exhaust steam is constantly meeting the return flow water from pipe 15 in the condenser 6 and replacing heat that may have been lost in circulation.

Obviously, while the system as a whole is advantageous in that it permits a sub-surface location of the separator 3 without interfering with the delivery of the volatiles of the elevated condenser, a number of the advantages incident to the system could be realized by some other location of the separator 3.

I claim:

1. In a blowoff apparatus for boilers, a blowoff line adapted to be connected with a boiler and receive volatiles, liquid, and precipitate therefrom, a separator located at a relatively low level connected to receive all such blown off products from said line, a boiler-supplying water line, a tank connected to said boiler-supply line located at a relatively high level which adapts it to deliver water to the boiler by gravity, a condenser at a level which adapts it to deliver water of condensation to the tank by gravity, and a vapor pipe leading from the separator upward to said condenser.
2. In a blowoff apparatus for boilers, a blowoff line adapted to be connected with a boiler, a separator receiving blown off products through said line and in position to drain the boiler by gravity, a boiler supplying line, a tank in position to feed said supplying line by gravity, a vapor pipe leading

from said separator, and a condenser receiving vapor from said vapor pipe and located to deliver to said tank by gravity.

3. In a blowoff apparatus for boilers, a blowoff line adapted to be connected with a boiler, a separator receiving blown off products through said line and in position to drain the boiler by gravity, a boiler supplying line, a tank in position to feed said supplying line by gravity, a vapor pipe leading from said separator, a condenser receiving vapor from said vapor pipe and located to deliver to said tank by gravity, a low capacity circulating line connecting the end of said boiler supplying line with said tank, and a pump for forcing water through said circulating line.

4. In a blowoff apparatus for boilers, a blowoff line adapted to be connected with a boiler, a separator receiving blown off products through said line and in position to drain the boiler by gravity, a boiler supplying line, a tank in position to feed said supplying line by gravity, a vapor pipe leading from said separator, a condenser receiving vapor from said vapor pipe and located to deliver to said tank by gravity, a low capacity circulating line connecting the end of said boiler supplying line with said condenser, a steam pump adapted to force water through said circulating line to said condenser, and means delivering exhaust steam from said pump to said vapor pipe.

Signed at Chicago, Illinois, this 9 day of October, 1922.

SPENCER OTIS.
